(57) **CLAIM**

The ornamental design for a plate for magnetic device mount, as shown and described.

DESCRIPTION

FIG. 1 is a front perspective view showing a first embodiment of a plate for a magnetic device mount of the present invention;

FIG. 2 is a side view thereof;

FIG. 3 is a front plan view thereof;

FIG. 4 is a bottom view thereof;

FIG. 5 is a rear plan thereof;

FIG. 6 is a front plan view thereof with those features shown in phantom presented for exemplary purposes only and forms no part of the claimed design;

FIG. 7 is a front perspective view showing a second embodiment of a plate for a magnetic device mount of the present invention;

FIG. 8 is a side view thereof;

FIG. 9 is a front plan view thereof;

FIG. 10 is a bottom view thereof;

FIG. 11 is a rear plan thereof; and,

FIG. 12 is a front plan view thereof with those features shown in phantom presented for exemplary purposes only and forms no part of the claimed design.

1 Claim, 4 Drawing Sheets
